DESIGN FOR A CIGARETTE CASE

Walton B. Crane, Beverly Hills, Calif., assignor to Allied Plastics Company, Los Angeles, Calif., a copartnership composed of Dwight C. Hirsh and Harry G. Long

Application May 9, 1944, Serial No. 113,523

Term of patent 14 years

(Cl. D85—2)

To all whom it may concern:

Be it known that I, Walton B. Crane, a citizen of the United States of America, residing at Beverly Hills, in the county of Los Angeles, State of California, have invented a new, original, and ornamental Design for a Cigarette Case, of which the following is a specification, reference being had to the accompanying drawing, forming a part thereof.

Fig. 1 is a perspective view of a cigarette case in closed position, showing my new design;

Fig. 2 is a perspective view of the cigarette case in open position;

Fig. 3 is a longitudinal sectional view on a slightly enlarged scale, the direction of view being indicated on the line 3—3 of Fig. 1; and

Fig. 4 is a transverse sectional view on a slightly enlarged scale, the direction of view being indicated on the line 4—4 of Fig. 1.

I claim:

The ornamental design for a cigarette case, as shown.

WALTON B. CRANE.
